(57) **CLAIM**

The ornamental design for a loudspeaker, substantially as shown and described.

DESCRIPTION

FIG. 1 is a front perspective view of the loudspeaker in accordance with the present design;

FIG. 2 is a back perspective view of the loudspeaker shown in FIG. 1;

FIG. 3 is a front view of the loudspeaker shown in FIG. 1;

FIG. 4 is a back view of the loudspeaker shown in FIG. 1;

FIG. 5 is a left view of the loudspeaker shown in FIG. 1;

FIG. 6 is a right view of the loudspeaker shown in FIG. 1;

FIG. 7 is a top view of the loudspeaker shown in FIG. 1; and,

FIG. 8 is a bottom view of the loudspeaker shown in FIG. 1.

Features indicated in phantom (broken line) are for exemplary purposes only and form no part of the claimed design.
FIGS. 5 and 6 are on an enlarged scale.
